UNITED STATES PATENT OFFICE.

MINA L. PETERS, OF SEATTLE, WASHINGTON.

DESIGN FOR A BOUDOIR CAP.

Application filed December 9, 1926. Serial No. 20,003. Term of patent 3½ years.

To all whom it may concern:

Be it known that I, MINA L. PETERS, a citizen of the United States, residing at Seattle, in the county of King and State of Washington, have invented a new, original, and ornamental Design for Boudoir Cap, of which the following is a specification, reference being had to the accompanying drawing, forming part thereof.

In the drawing;

Fig. 2 is a view in three-quarters rear perspective of the same.

I claim:

The ornamental design for a boudoir cap as shown.

MINA L. PETERS.
